CLAIM

The ornamental design for a counter, as shown and described.

DESCRIPTION

FIG. 1 is a front, top, and right side perspective view of a counter showing a first embodiment our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a front view thereof in an alternate illuminated state;

FIG. 8 is a front view thereof in an alternate illuminated state;

FIG. 9 is a front view thereof in an alternate illuminated state;

FIG. 10 is a front, top, and right side perspective view of a counter showing a second embodiment our new design;

FIG. 11 is a front view thereof;

FIG. 12 is a left side view thereof;

FIG. 13 is a right side view thereof;

FIG. 14 is a top view thereof;

FIG. 15 is a bottom view thereof; and,

FIG. 16 is a front view thereof in an alternate illuminated state.

The dashed broken lines in the figures show portions of the counter that form no part of the claimed design. The radiating lines illustrate the glow of illumination emanating from the setup keys.
